UNITED STATES PATENT OFFICE.

MONTROVILL D. CUMMINGS, OF COLUMBUS, OHIO.

MAIL-SACK CATCHING AND DELIVERING MECHANISM.

SPECIFICATION forming part of Letters Patent No. 568,747, dated October 6, 1896.

Application filed August 22, 1895. Serial No. 560,108. (No model.)

To all whom it may concern:

Be it known that I, MONTROVILL D. CUMMINGS, a citizen of the United States, residing at Columbus, in the county of Franklin and State of Ohio, have invented a certain new and useful Improvement in Mail-Sack Catching and Delivering Mechanisms, of which the following is a specification.

My invention relates to the improvement of mail-sack catching and delivering mechanisms of that class which are employed where mail is received by and discharged from a moving train; and the objects of my invention are to provide a simple and effective mechanism of this class of superior construction and arrangement of parts by means of which mail-sacks may be delivered and caught in a safe and convenient manner, and to produce other improvements the details of construction of which will be more fully pointed out hereinafter. These objects I accomplish in the manner illustrated in the accompanying drawings, in which—

Figure 1 is a partial transverse section of a car having my improvement thereon and showing adjacent thereto my improved mail-crane in elevation. Fig. 2 is a detail view in perspective illustrating the manner of journaling the car-crane standard. Fig. 3 is a detail view in perspective of one of the trackway crane-arm ends. Fig. 4 is a view in perspective of the inner side of a mail-car, showing the position of the car-crane when not in use. Fig. 5 is a similar view showing the position of the car-crane parts when the same is ready for swinging outward through the doorway. Fig. 6 is a plan view of the car and track cranes. Fig. 7 is a view in elevation of the sack-receiving yoke. Fig. 8 is a sectional view on line $x-x$ of Fig. 7. Fig. 9 is an enlarged sectional view on line $y-y$ of Fig. 7. Fig. 10 is a view in elevation of the receiving-yoke and its supporting-arm, and Fig. 11 is a central vertical section of the track-crane.

Similar numerals refer to similar parts throughout the several views.

In carrying out my invention I employ adjacent to a railway-track a crane-standard 1, the latter consisting of upper and lower sections 2 and 3. The lower and tubular section of this standard is preferably provided

with a suitable enlarged base 4, while over the upper end of said standard-section 3 fits loosely a cap 5, the latter being provided with a central opening in its upper side and a short vertical upwardly-extending neck 6 about said opening.

7 represents a collar which is provided with a flanged upper portion, said collar being secured, as indicated, about the tubular section 3 at a point below the cap 5. The flanged upper portion of the collar 7 has its periphery provided with ratchet-teeth, as indicated at 8. The lower portion of the upper and smaller standard-section 2 extends into the section 3, passing through the opening of the cap 5 and its neck portion 6, to which said section 2 is secured. The inner end portion of the section 2 also passes loosely through an internal collar or washer 9, which fits within the section 3 and which is provided with a circumferential groove or keyway 10.

11 represents a set-screw which, as shown, is adapted to be supported adjustably in the wall of the section 3 and the inner end of which is adapted to bear in the groove 10 of the internal collar 9.

12 represents a coiled spring which loosely surrounds that portion of the standard-section 2 which is within the section 3, said spring having its upper end connected, as indicated at 13, with the cap 5, and having its lower end connected with the internal collar 9.

14 represents a tubular arm the inner bifurcated end portion of which is pivotally connected with opposite sides of the cap-neck 6. As indicated in the drawings, this tubular arm 14 consists of an external tube portion 15, within which is rotatably inclosed a tube 16. Within the inner tube 16 is provided a locking or plunger rod 17, the latter being adapted to slide loosely within said tube and being adapted to project, as shown, through the outer end thereof. About the outer surface and forward portion of the external tube 15 I provide a sliding keeper 18, the latter being provided with an upper and lower forwardly-extending lip portion 19. Within the tube 16 is secured one end of a short spring-strip 20, the latter being so bent as to normally exert a spring-pressure on the rod 17.

21 represents a substantially U-shaped

catch or yoke, the ends of which are preferably made to flare outwardly, as shown, one of the side arms of this yoke being connected with the forward end of the tubular arm 14, 5 while the locking-rod 17 passes loosely through said yoke-arm. This yoke 21 is adapted to be supported in the horizontal position shown in the drawings by moving the sliding keeper 18 outward until its lips embrace, as indicated, the upper and lower sides of the inner arm of the yoke. The under side of the external tube 15 is provided, as indicated at 22, with a short downwardly-projecting blade or tooth, which, when said 15 arm is dropped downward, as indicated more clearly in Fig. 11, is adapted to engage with the ratchet-teeth of the collar 7, and thereby prevent a backward rotation of said arm. With the outer end portion of the tooth 22 is 20 loosely connected the upper end of a brace-rod 25.

26 represents the upper crane-arm, the rear end portion of which is bifurcated, said bifurcated portion being bent upward and thence outward, as indicated at 27. This bifurcated portion of the arm 26 is pivoted at 28 to the upper portion of the standard-section 2, while the rearwardly-extending members of said arm have connected therewith the upper ends 30 of spring-rods 29. The lower ends of these spring-rods are, as indicated, pivotally connected with opposite sides of the rear portion of the lower crane-arm 14, said spring-rods being of such length as to result in their bowing rearwardly when the upper and lower crane-arms are supported in a horizontal position, as indicated in Fig. 1 of the drawings. The outer end of the upper crane-arm 26 is provided with a swivel-pin 30, while a similar 40 pin 30^a is provided on the outer side of the yoke 21.

31 represents a portion of a mail-car, said car being provided with a doorway 32, the latter being adapted to be closed by a sliding 45 door 33. Above the doorway and extending to one side thereof I provide an angular guide-bar 34, behind the downturned face of which is adapted to slide the upper portion of the car-door. From this guide-bar 34, and 50 on each side of the center of the width of the doorway, project two lugs 35, the outer end portions of which are provided with openings through which are adapted to pass the vertical arms of a staple 36.

55 On the car-floor and in front of the doorway I secure a flat guide-bar 37, the latter being provided at points vertically beneath the pairs of lugs 35 with sockets 38. In constructing my improved car-sack crane I provide a 60 vertical rod 39, the latter having a crank-shaped termination 40 at each end. The upwardly-turned end portion of the upper crank 40 is adapted to pass loosely between the lugs of one of the pairs 35, while said upturned crank portion is provided with a collar 41, which is adapted by contact with the under-sides of said lugs to limit the upward move-

ment of the crank. That portion of the crank which is thus inserted between said lugs is, as shown in the drawings, in rear of 70 the staple 36, the latter thus serving to prevent any outward movement of the crank. The downturned end portion of the lower crank 40 is, as indicated, adapted to be journaled in that socket 38 which is vertically 75 below the bearing of the upper crank termination. The vertical portion of the rod 39 is loosely inclosed by a tubular casing 42. Surrounding the upper portion of the casing 42 is a sleeve 43, from which projects at right 80 angles therewith the upper crane-arm 44. In order to retain the sleeve 43 in desirable frictional contact with the casing 42, I provide set-screws 45, which pass through said sleeve-wall and are adapted to bear against 85 said casing. About the inner end portion of the arm 44 I provide a split sleeve 46, the latter being provided with outwardly-projecting lips which are adjustably connected by bolts in the usual manner. From this 90 sleeve 46 extends outward a catch-arm, the latter being preferably of the substantially S shape shown and extending in a direction inclined from the direction of the arm 44, thus forming an acute angle between said 95 arms. The catch-arm 57 is provided in its outer end portion with a spring-strip 58, one end of which is secured to said arm. The outer end of the arm 44 has swiveled therein an outwardly-projecting sack-holding pin 59. 100

60 represents the lower car-crane arm, the inner end of which is jointedly connected at 61 with the lower end portion of the tubular casing 42. This arm 60 is also provided in its outer end with a swivel sack-holding pin 105 62, and said arm 60 is normally retained in a slightly-depressed position by means of a spring-strip 63, one end of which is secured to said arm and the remaining end of which is secured to the casing 42. 110

When the car-crane is not in use, it may be turned to the position indicated in Fig. 4 of the drawings, that is, with the arms 44 and 60 against the inner side of the car-door, the vertical rod 39 being thus thrown to a position within the car and adjacent to one side of the doorway thereof. When it is desired to put said car-crane into use, the arms thereof may be turned to the position indicated in Fig. 5 of the drawings, that is, so that they project 115 inwardly at right angles with the car side, after which the arm 57 may be turned upward to the substantially horizontal position indicated. This being accomplished the sack, which is indicated in dotted lines in 120 Figs. 4 and 1 of the drawings, may have its ends engaged, respectively, with the upper and lower supporting-pins 59 and 62, said sack thus being suspended between the outer end portions of the crane-arms. The door 125 being opened the crane-standard 39 may be so rotated as to bring its body on the outer side of the car-doorway to the position indicated in Fig. 1. In this manner it will be 130

observed that the sack-supporting arms of the car-crane will be made to suspend the sack in a vertical position on the outer side of the car, while the spring-strip 58 of the arm 57 will come into contact with the inner side of the car adjacent to the doorway, as shown in Fig. 6, thus limiting the outward movement of the car-crane and providing a cushion-bearing for said crane against the car.

10 In order to illustrate the manner of catching and delivering mail-sacks by the mechanism herein described, we will assume that the sack to be caught by the car, and which is indicated in dotted lines at 65, is suspended between the supporting-pins of the upper and lower arms 26 and 14 of the track-crane. This connection of said arms must result, as will readily be seen, in bringing the latter to a substantially horizontal position and in bowing the spring-rods 29 outward. By thus suspending the sack between two spring-actuated arms it will be seen that a sufficient upward and downward strain will be had on the ends of said sack to hold the latter against dis- placement by high winds or similar causes. The track-crane arms being in the position described the locking-rod 17 of the arm 14 is pressed within the tube 16 and the yoke 21 is retained by the keeper 18 in a horizontal position with its mouth in the direction from which the train approaches. When the swiftly-moving train reaches the track-crane, the sack to be delivered, and which is indicated in dotted lines at 67, has its central portion caught within the yoke 21, and the force of the blow thus imparted to said yoke must result, as will readily be seen, in imparting a rotary motion to the standard-section 2. The centrifugal force thus imparted to the lower 40 arm 14 results in the locking-rod 17 being thrown outward between the side arms of the yoke and in the sack being thus locked within said yoke. It is evident that the rotary movement of the arm 14 will result in a dis- engagement of the brace 25 with the collar 7, and that when such rotary force is sufficiently spent the straightening of the spring-rods 29 will serve to drop the arm 14 downward and raise the arm 26 upward to the position indi- 45 cated in Fig. 11. This downward dropping movement of the arm 14 results in the engagement of the tooth 22 with the ratchet-teeth of the collar 7, thereby preventing any backward rotation of said arm.

50 The rotary movement imparted to the standard-section 2 above described must result, as will readily be seen, in a winding of the spring 12, the latter thus serving to gradually de- crease the momentum imparted by the force 55 of the blow of the sack against the yoke.

Simultaneously with the delivery above de- scribed of the sack 67 the central portion of the sack 65 is caught in the angle between the arms 44 and 57 of the car-crane, and the 60 force of the blow thus imparted to the arm 57 and the consequent rebound of the sack against the arm 44 results in the car-crane be-

ing swung inward to the position indicated in Fig. 4 of the drawings. In this manner it will be seen that the operations of catching 70 and delivering mail-sacks at a station may be accomplished simultaneously, and that safe, reliable, and at the same time comparatively simple means are employed in accomplishing this object.

75 In case it is desired to change the position of the car-crane so that its arms, when projected from the car, will extend in the direction in which the car is moving it is evident that the crank-bearings of the standard 39 may be readily changed to the remaining pair 80 of lugs 35 and socket 38, thus reversing the position of said crane. In order to reverse the position of the sack-catching yoke of the track-crane, the keeper or catch-sleeve 18 may 85 be forced inward until the yoke is disengaged therefrom, thus admitting of the yoke being reversed, after which said keeper may be re-engaged therewith.

90 In case it is desired to hold the crane-arms 14 and 26 in horizontal or substantially horizontal positions when said arms are not connected by a sack the lower and free end of the brace-arm 25 may be made to engage with the upper side of the collar 7, said brace thus 95 acting as a prop to retain said crane-arms in the desired positions. It is obvious that this brace will be of great utility when it is simply desired to support the arms in position for catching a sack or when it is desired to 100 hold them in a convenient position for attaching or suspending a sack between them.

Having now fully described my invention, what I claim, and desire to secure by Letters Patent, is—

105 1. In a mail-sack catching and delivering mechanism the combination with the standard 1 formed of two sections, one of said sections being rotatively supported by the other and a coil-spring the respective ends of which are 110 connected with the upper and lower standard-sections, of sack-supporting arms fulcrumed to said rotating standard-section, said sack- supporting arms having their rear portions 115 connected by spring-rods, substantially as and for the purpose specified.

120 2. In a mail-sack catching and delivering mechanism the combination with the track- crane standard consisting as described of upper and lower sections, said upper section 125 being journaled in said lower section, a collar 7 surrounding said lower section and a coil- spring connecting said upper and lower sections as described, of upper and lower sack- supporting arms fulcrumed to said upper sec- 130 tion, a spring-rod connection between the rear portions of said crane-arms and a brace having a pivotal connection with said lower crane- arm and adapted to bear upon the collar 7, substantially as and for the purpose specified.

135 3. In a mail-sack catching and delivering mechanism the combination with the track- crane standard consisting of upper and lower sections, said upper section being adapted to

rotate within said lower section and having a spring connection therewith as described and a collar 7 on said lower section, the latter having a toothed periphery, of crane-arms 26 5 and 14 fulcrumed to said rotating standard-section, a spring-rod connection as described between said crane-arms, and a projecting tooth formed on the lower side of said arm 14, said tooth being adapted to drop into engagement with the ratchet-teeth of said collar when said arm is dropped downward substantially as and for the purpose specified.

4. In a mail-sack catching and delivering mechanism the combination with a crane-standard and arms fulcrumed thereto, a substantially U-shaped sack-yoke pivotally connected with the outer end of one of said arms and a locking-pin loose in said arm, said pin adapted by the centrifugal motion of said 15 arm to be thrown out across said yoke substantially as and for the purpose specified.

5. In a mail-sack catching and delivering mechanism the combination with a track-standard, an upper arm 26 fulcrumed to said 25 standard and adapted to engage the upper end of a sack, of a lower tubular arm 14 having its rear portion fulcrumed to said standard, a rotatable tube 16 within said arm 14, a sliding pin 17 within said tube 16, a substantially U-shaped yoke 21 supported from 30 the outer end of said tube 16 and means for rotating said yoke to a horizontal position

said rod 17 adapted to pass through and across said yoke substantially as and for the purpose specified.

6. In a mail-sack catching and delivering mechanism the combination with a car having a doorway therein, of a car-crane standard 39 having crank-shaped terminations, said crank terminations detachably journaled 40 above and below said car-door, arms 44 and 60 extending from said standard 39, means for suspending a sack between said arms and an inclined arm 57 extending from the rear portion of said arm 44 as described, substantially as and for the purpose specified.

7. In a mail-sack catching and delivering mechanism the combination with a car having a doorway therein, a car-crane standard 39 having crank-shaped terminations, said 45 cranks having bearings above and below said car-doorway and a casing 42 surrounding said standard 39, of an arm 44 extending from the upper portion of said casing 42 and adjustably connected therewith, a catching-arm 50 57 extending at an incline from said arm 44 and a normally-depressed arm 60 extending from the lower portion of said casing 42, substantially as and for the purpose specified.
